UNITED STATES PATENT OFFICE.

KNUT ALFRED READ, OF OSKALOOSA, IOWA.

FIRE HYDRANT.

Application filed October 14, 1926. Serial No. 141,527.

This invention relates to fire hydrants, and particularly, to the drain valves used in such devices for permitting water to escape from the stand pipe after the water supply valve of the hydrant has been closed.

One object of my invention is to provide a drain valve for fire hydrants, that is of novel construction and such design that long periods of non-use will not cause it to stick or fail to effectively close the drain opening of the stand pipe when it is moved into its closed position upon opening the water supply valve of the hydrant.

Another object is to provide a reliable drain valve for fire hydrants, which is of such design that it will be forced tightly against its co-operating valve seat by positive pressure exerted on same by a novel means that is actuated during the operation of opening the supply valve to admit water to the stand pipe.

And still another object of the invention is to provide a fire hydrant in which the drain valve is moved positively towards and away from its seat during the operation of opening and closing the water supply valve by a device that has a screw threaded connection with the operating rod that is used to open and close the water supply valve, said drain valve being so constructed that it will seat by gravity at approximately the beginning of the opening movement of the water supply valve. Other objects and desirable features of my invention will be hereinafter pointed out.

Figure 1 of the drawings is a side elevational view, partly broken away, of a fire hydrant constructed in accordance with my invention.

Figure 2 is an enlarged side elevational view, partly in vertical section, of the drain valve;

Figure 3 is a horizontal sectional view, taken on approximately the line 3-3 of Figure 2; and

Figure 4 is a detail sectional view of the device that is used to take up end play between the valve operating rod and the actuating device in the cap of the stand pipe.

Referring to the drawings, which illustrate the preferred form of my invention, A designates the stand pipe of a fire hydrant, B designates the main valve through which water is admitted to said stand pipe from a source of supply, C designates as an entirely a drain valve that closes a drain opening at

the lower end of the stand pipe through which water escapes from the stand pipe after the supply valve B has been closed, and D designates an operating rod that is used to open and close the supply valve B, and to impart movement to an actuator that positively moves the drain valve towards and away from its seat. In view of the fact that the drain valve is normally open and frequently stands at rest for long periods, it is highly important that it be of such construction and design that long periods of non-use will have no effect on same and will have no tendency to cause it to stick or get into such a condition that it will not successfully perform its function when it is moved into its closed position upon opening the water supply valve B. The drain valve C of my improved hydrant has this desirable characteristic, and moreover, it is so constructed that it will seat automatically as soon as the water supply valve B starts to open, will be forced tightly against its seat at substantially the completion of the opening movement of the water supply valve, will remain seated while said supply valve is being closed and will be moved positively away from its seat at substantially the completion of the closing movement of the water supply valve and thereafter held out of engagement with said seat or with any portion of the valve casing until the water supply valve is again opened.

As shown clearly in the drawings, the drain valve C comprises a tubular casing 1 that is arranged in an upright position in a horizontally-disposed partition 2 or end wall at the lower end of the stand pipe A, a vertically-movable valve element 3 inside of the casing 1 and a horizontally-disposed valve seat 4 inside of said casing that surrounds a drain opening 5. In the form of my invention herein illustrated the valve element 3 is tapered or of substantially frusto-conical form and is arranged above the valve seat 4 which is also tapered, but I wish it to be understood that it is not essential that said valve element and valve seat be of this particular construction or arrangement, so long as the valve element is of such design that it is not apt to stick or adhere to the valve seat or to any portion of the valve casing when the drain valve is in its inoperative or open position, thereby making it practicable to form the active face of the valve element 3 from rubber, leather or some other non-me-

tallic material that has some inherent resiliency.

In order that the drain valve will seat as soon as the water supply valve B starts to open, and will be forced tightly against its seat by positive pressure exerted on same just before the supply valve B reaches its wide open position, and in order that the drain valve will remain seated when said supply valve B starts to close, and will be unseated by positive pressure exerted on same at substantially the completion of the closing movement of said supply valve, I provide the valve element 3 of the drain valve with a stem 6 that projects upwardly through a valve actuator 7 to which a vertical reciprocating movement is imparted by the rod D when said rod is rotated to open and close the water supply valve B, said valve actuator 7 being so arranged that it will exert a downward thrust on the valve element 3, thus forcing it tightly against its seat 4, during the last few turns of the rod D in the operation of opening the supply valve and will exert an upward thrust on a head piece 6^a at the upper end of the valve stem 6, thus positively moving the valve element 3 away from its seat during the last few turns of the rod D in the operation of closing the supply valve B. The valve actuator 7 is of considerably less length than the valve stem 6 and is provided with a center hole through which said stem passes, said stem and center hole being preferably of circular shape in cross section, so as to permit the valve element 3 to rotate relatively to its seat 4.

In order that vertical reciprocating movement will be imparted to the valve actuator 7 by the rotary movement of the rod D, the lower end of said rod is rigidly connected to a sleeve 8 that virtually forms part of the rod D, and which is equipped with internal screw threads that mesh with external threads on a portion 9 at the upper end of the actuator 7, means being provided for preventing said actuator from turning with the sleeve 8 when said sleeve is rotated by the rod D. Various means can be used for this purpose, but I prefer to arrange a bearing member 10 in the upper end portion of the valve casing 1 that is equipped with a non-circular-shaped opening through which a non-circular-shaped portion 7^a of the valve actuator 7 passes and provided with laterally-projecting wings 11, one of which is adapted to bear against the inside of the stand pipe A, as shown in Figure 3, and thus prevent the bearing member 10 from turning relatively to the valve casing 1 during the operation of rotating the rod D to open and close the water supply valve B. The internally-screw-threaded sleeve 8, attached to the lower end of the rod D of the valve operating mechanism, is provided at its lower end with a ta-

pered portion that rotates on a tapered surface on the bearing 10 when the rod D is turned, and some suitable means is provided for preventing the sleeve 8 from moving vertically relatively to said bearing member 10, such, for example, as screws 12 arranged horizontally in lugs 13 on said bearing member and adapted to lap over a flange or annular rib 14 on the lower end of the sleeve 8, as shown clearly in Figure 2. It is immaterial how the valve casing 1 is mounted in the partition or end wall 2 of the stand pipe, but one convenient way of mounting said valve casing is to provide it with an externally-screw-threaded portion 15, as shown in Figure 2, that is screwed into a hole in the horizontal partition or end wall 2 of the stand pipe.

When the water supply valve B is open the valve actuator 7 is in engagement with the valve element 3 and holds said valve element tightly against its seat 4. To close the supply valve B the rod D is rotated in one direction, which operation causes the valve actuator 7 to move upwardly away from the valve element 3, but without causing said valve element 3 to become unseated. During the last turn or two of the rod D in the operation of closing the supply valve B, the valve actuator 7 engages the head piece 6^a on the valve stem 6 and exerts a positive upward thrust on said stem, thereby causing the valve element 3 to be moved upwardly away from its seat and held in a raised position out of contact with said seat or with any portion of the valve casing to which it might adhere during a long period of non-use. The next time the hydrant is used the rod D is rotated in the opposite direction, so as to open the water supply valve B, and during the first turn or two of the rod D, the actuator 7 will be moved downwardly slightly, whereupon gravity causes the valve element 3 to drop into engagement with its seat 4 and close the drain opening 5. Said valve element remains in this condition during the operation of opening the supply valve B, and at approximately the time said supply valve reaches its wide open position, the valve actuator 7 engages the valve element 3 and forces it tightly against its seat.

From the foregoing it will be seen that in a fire hydrant of the construction above described there is little liability of the drain valve getting into such a condition that it will not effectively close the drain opening of the stand pipe when the water supply valve B of the hydrant is opened, due, of course, to the fact that the valve element 3 of the drain valve is normally spaced away from any portion of the valve casing to which it can stick or adhere during a long period of non-use. Moreover, the drain valve will seat by gravity as soon as the water supply valve starts to open, and as it

is forced tightly against its seat by positive pressure exerted on same at substantially the completion of the opening movement of the water supply valve by a screw-threaded connection between the valve actuator and a threaded member on the rod D, there is no liability of water escaping from the stand pipe through the drain opening when the water supply valve is in its open position.

10 These desirable features, coupled with the fact that the drain valve is of exceptionally rugged construction, makes my hydrant an improvement upon the fire hydrants now in general use.

15 In fire hydrants of the type to which my invention relates it is the usual commercial custom to mount a rotatable actuating device 16 in the cap 17 at the upper end of the stand pipe A and provide said actuating device with a non-circular-shaped socket that receives a non-circular-shaped portion on the upper end of the valve operating rod D, said socket being made deep enough to provide sufficient end play or lost motion between

25 the end of the valve operating rod and the end wall of the socket in the actuating device 16 to compensate for variations in the castings from which the stand pipe is constructed. In my improved hydrant it is

30 necessary that the valve operating rod D be of such construction that it cannot move upwardly when the valve actuator 7 is pressing the movable element 3 of the drain valve downwardly against its seat 4. Accordingly,

35 I mount a solid or one piece actuating device 16 in the cap 17 of the stand pipe and provide said actuating device with an adjustable bearing 18, accessible from the upper end of the device 16 when said device is

40 arranged in operative position in the cap 17, that is adapted to be moved downwardly into engagement with the valve operating rod D, so as to take up any end play or lost motion between the rod D and the actuating device

45 16 and thus eliminate the possibility of the valve actuator 7 moving upwardly when the drain valve is seated. As shown in Figure 4, the adjustable bearing 18 just referred to is formed by a screw mounted in the actuating device 16 in such a manner that the end of

50 said screw can be moved downwardly into engagement with the upper end of the rod D that projects into the socket 19 in the actuating device 16. Said device 16 is provided

55 with a bore 20 terminating in the upper end of said device through which a screw driver can be passed and inserted in a screw driver slot in the upper end of the bearing 18 to adjust said screw upwardly or downwardly,

60 the upper end of said bore being normally closed by a plug 21 that is removably mounted in the upper end of the device 16.

Having thus described my invention, what I claim as new and desire to secure by Letters Patent is;

1. A fire hydrant provided with a water supply valve, a mechanism for opening and closing said supply valve comprising an operating rod, a gravity-operated drain valve that seats automatically as soon as said supply valve starts to open, a seat for said drain valve and a means joined to said operating rod by a screw-threaded connection for forcing said drain valve tightly against its seat at substantially the completion of the opening movement of said supply valve.

2. A fire hydrant provided with a water supply valve, a rotatable operating rod for actuating said supply valve, a gravity operated drain valve that seats automatically at substantially the beginning of the opening movement of said supply valve, and a reciprocating means joined to said operating rod by a screw-threaded connection for positively moving said drain valve away from its seat during the operation of closing said supply valve and for positively moving said drain valve into engagement with its seat during the operation of opening said supply valve.

3. A fire hydrant provided with a water supply valve, a rotatable operating rod for actuating said valve, a drain valve, and a reciprocating actuator for said drain valve joined to said operating rod by a screw-threaded connection and arranged so as to permit said drain valve to seat automatically as soon as the supply valve starts to open, to be forced tightly against its seat at approximately the completion of the opening movement of the supply valve, to remain seated during the major portion of the closing movement of the supply valve and to be moved positively away from its seat at approximately the completion of the closing movement of the supply valve.

4. A fire hydrant provided with a water supply valve, an operating mechanism for same comprising a rotatable rod, a drain valve comprising a valve element and a co-operating valve seat arranged horizontally underneath the same, a stem on said valve element, an actuator surrounding said valve stem and arranged so that it is capable of moving longitudinally relatively to said stem, and a means operated by said rotatable rod for reciprocating said valve actuator and causing the same to force said valve element tightly against its seat at a certain period in the cycle of operations of said valve operating mechanism and to exert pressure on said stem in a direction to lift said valve element from its seat during a different portion of the cycle of operations of said valve operating mechanism.

5. A fire hydrant, comprising a stand pipe provided adjacent its lower end with a horizontally-disposed partition, a tubular valve casing carried by said partition and provided with a horizontally-disposed valve seat, a

valve element in said casing arranged above said seat, a stem projecting upwardly from said valve element and provided at its upper end with a head piece or projection, a reciprocatingly mounted actuator about said stem, an operating rod provided with an internally screw-threaded portion that engages external screw threads on said actuator, and means for preventing said actuator from rotating with said rod.

6. A fire hydrant, comprising a stand pipe provided adjacent its lower end with a horizontally-disposed partition, a tubular valve casing carried by said partition and provided with a horizontally-disposed, tapered valve seat, a tapered valve element in said casing

arranged above said seat, a stem projecting upwardly from said valve element and provided at its upper end with a head piece or projection, a reciprocatingly mounted actuator about said stem, an operating rod provided with an internally screw-threaded portion that engages external screw threads on said actuator, a bearing member in said valve casing provided with a portion that co-operates with said stand pipe to hold said bearing member against rotary movement, and a non-circular-shaped portion on said actuator that passes through a non-circular-shaped hole in said bearing member. 25
